Primary Examiner — Raphael Barkai*Assistant Examiner* — Randall Gholson(74) *Attorney, Agent, or Firm* — Foley & Lardner LLP**(57) CLAIM**

I claim the ornamental design for a mount portion for use with audio/visual devices or the like, as shown and described.

DESCRIPTION

FIG. 1 is a top perspective view of a mount portion for use with audio/visual devices or the like showing my new design, wherein the break line indicates indeterminate length;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The ornamental design which is claimed is shown in solid lines in the drawings. The dash-dot-dash lines define a boundary of the claimed design. The dash lines in the drawings are for illustrative purposes only and form no part of the claimed design.
